UNITED STATES PATENT OFFICE.

HERMAN JAKOBSSON, OF PHILADELPHIA, PENNSYLVANIA.

CONTINUOUS-PULL FIRING MECHANISM FOR GUNS.

1,293,103.

Specification of Letters Patent.

Patented Feb. 4, 1919.

Application filed February 28, 1917. Serial No. 151,406.

To all whom it may concern:

Be it known that I, HERMAN JAKOBSSON, a citizen of the United States, residing at Philadelphia, county of Philadelphia, and 5 State of Pennsylvania, have invented a new and useful Improvement in Continuous-Pull Firing Mechanism for Guns, of which the following is a full, clear, and exact description, reference being had to the accompanying 10 drawings, which form a part of this specification.

The object of my invention is to provide a new and improved firing mechanism for breech loading guns. The invention is particularly applicable to that well known type 15 of gun in which the breech block moves in and out of the breech in a direction transverse to the axis of the bore, whether in a vertical, horizontal or inclined plane, the opening movement taking place, preferably, 20 automatically during the counter recoil of the gun and the closing movement also taking place automatically on the insertion of a fresh projectile and cartridge case. The invention is also applicable to a gun in 25 which the breech block is manually operated. The cocking and firing takes place by a continuous pull on the trigger, that is to say the hammer is cocked at the beginning 30 of the trigger pull and released toward the end of the pull.

In describing the present invention I shall also, for purposes of clearness, describe the breech block actuating mechanism, and refer 35 briefly to the cartridge extractor and shoulder piece carrying the firing handle, but the construction embodying the cartridge extractor and shoulder piece are not herein claimed, as the same form the subject-matter 40 of co-pending applications, Serial No. 151,407 and Serial No. 151,408, filed of even date herewith.

A preferred embodiment of my invention is shown in the accompanying drawings, in 45 which,—

Figure 1 is an elevation of a gun and carriage with parts broken away.

Fig. 2 is a horizontal section, on line 2—2 of Fig. 5, through the breech end of the 50 gun showing the breech block, in plan view, in open position.

Fig. 3 is a view similar to Fig. 2 with the breech block shown in section and in closed position.

55 Fig. 4 is a vertical section substantially on line 4—4 of Fig. 3.

Fig. 5 is a transverse section on the line 5—5 of Fig. 3, looking toward the muzzle of the gun.

Fig. 6 is a perspective view of the breech 60 block.

Fig. 7 is an explanatory detail view of the firing mechanism.

Fig. 8 is a detail perspective view of the 65 end of the cocking sleeve.

Figs. 9 and 10 are longitudinal sectional views showing the firing mechanism in different positions.

Fig. 11 is a detail perspective view of the 70 hammer-retracting rocker lever.

Fig. 12 is an elevation of a portion of the 75 manual devices for actuating the trigger of the firing mechanism.

Fig. 13 is a sectional view on the line 13—13 of Fig. 12.

Fig. 14 is an end view of the parts shown 75 in Fig. 12.

30 represents the gun which is mounted on trunnions 29 on the carriage 28. 31 is the gun chamber and 32 the breech provided 80 with a rearward opening 33 and a traverse opening or housing 34 in which the block or wedge 35 is made to slide in and out in the breech. The rear wall 36 of the housing is slightly inclined in conformity with the 85 taper of the block 35, so that when the mechanism is opened, that is, when the block moves out transversely to the bore axis, it may also have a slight rearward movement. To insure the breech block 35 contacting 90 with wall 36 in whatever position the block may be, a gib 37 and a corresponding groove 38 are provided respectively in the housing and the block, the direction of the gib and the groove being parallel with the wall 36. 95 The groove 38 opens into cam groove 41 in order to facilitate the assembling and disassembling of the mechanism.

An operating crank 39, journaled in a lug on the breech 32, and engaging, by means of 100 its head 40, a cam groove 41 in the block 35, controls the movement of the block. This crank 39 is actuated by a lever 42, having a handle 43 for manual operation and link connection 44 with some non-recoiling 105 part of the gun carriage, for automatic operation in a suitable manner. The normal turning of the crank 39 is about 90°, or in other words, from the crank head, as at 40° Fig. 2, in the closed position of the mechanism, to the crank head, as at 40, in the open 110 position of the mechanism. These limits

are controlled by the stop bolt 92, acting in the groove 93 in the breech block, as more fully described hereinafter.

An additional stop for the hand lever is provided by a plug 110 which is mounted to turn around the screw 111, on top of the gun, and is placed in such a position that the hand lever 42 strikes against the raised edge 112 when the head 40 of the operating crank stands in a position as at 40^a in Fig. 2, that is, in the closed position of the mechanism. Now in order to disassemble the mechanism, the stop bolt 92 is first removed and the plug 110 thereupon turned about 180 degrees, so that the raised edge 112 then stands on the opposite side to what is shown in Fig. 4 and the hand lever 42 will now be able to turn an additional angle, so that the head 40 of the operating crank 39 can swing into the position 40^b, as shown in Fig. 2. That is, the head is registering with the groove 38 in the breech block, which now may be removed from the breech of the gun.

In the center of the block is a bore or chamber 54 for the firing gear, consisting of a hammer or firing bolt 45 with a firing pin 46, surrounded by a cocking sleeve 47, which fits in the chamber 54, the latter being closed by a closing plate 48. The hammer 45 is guided partly in the cocking sleeve 47 and partly in a forwardly extending sleeve 57 on the closing plate 48 through the intermediary of the hammer shank 49. Between the hammer head and the closing plate 48 is inserted the coiled main or firing spring 50, tending to push the hammer muzzleward. Thus, when the gun is loaded, the firing pin will be stopped by the primer in the cartridge case 51, but when unloaded, the hammer head will strike the front wall of the chamber 54 when the trigger is pulled.

Between the closing plate 48 and the cocking sleeve 47 is inserted another coiled spring 52, which surrounds spring 50 and tends to push the cocking sleeve 47 muzzleward until it rests against the front wall of the chamber 54. The cocking sleeve is provided with one or more heels or lugs 53 projecting inward and engaging, with their rear faces, corresponding external heels 55 on the hammer 45. The side faces of the heels or lugs 53 and 55 are beveled at a suitable angle, say 30 degrees, for the purpose hereinafter described.

The sleeve 57 is provided with one or more helical slots 58 for a radial projection or lug 59 on the hammer shank 49. At the forward end of the slot is a transverse offset 60 on one side, into which the lug 59 can be turned, the other side of the slot 58 being unbroken. The firing spring 50, which acts not only under compression but also as a torsional spring, tends to hold the hammer lug 59 against the unbroken side of the slot 58 during travel of the hammer 45, and for

this purpose the spring 50 is provided with a teat at each end for engaging in corresponding recesses 61, 62 in the hammer and closing plate respectively.

The cocking sleeve 47 has a radial toe 63, serving both as a key against turning and as a means engaging with the trigger 64. A longitudinal keyway 65, cut in the breech block, grips the sides of the toe 63, and this keyway opens into the cut 66 provided for the trigger 64, which is fulcrumed on a removable spindle 67 so as to have sufficient throw to cock and fire the hammer through the intermediary of the cocking sleeve. The outer end of the trigger protrudes sufficiently beyond the face of the breech block to engage with the trigger link 68.

When the hammer is released by the sleeve lugs 53, the firing pin 46 protrudes beyond the front face of the breech block. The firing pin remains in this position until the sleeve 47 advances under the action of its spring 52. In the front end of the firing gear chamber 54 is placed a rocker 69 having trunnions 70 turning in bearings provided for them in the breech block. The rocker has two rearwardly projecting heads 71 and 72, which respectively engage with a forward portion of the hammer 45 and the sleeve 47 in such a manner that with the firing gear in position of rest (see Fig. 10), the pressure of spring 52 is sufficient to overcome the pressure of the main spring 50 and retract the hammer 45 until the firing pin point stands well within the block. As this is the position the firing gear has when at rest and at the moment of closing the mechanism, there is no possibility of premature firing.

To prevent rattling when the sleeve and hammer are retracted, the small spring 73 may be provided engaging a tail 74 on the rocker, thus keeping the latter pressed against the forward wall of the chamber 54; see Fig. 9, which shows the position of the parts at the moment the gun is fixed and before the trigger is released.

To one side of, or below, the firing gear is placed a hammer retracting crank having two arms 75 and 76 connected by means of a spindle 77 which rests in a bearing in the breech block. The arm 75 engages with the forward face of the sleeve 47 and a nose 76^a on the arm 76 projects into the groove 41 (see Fig. 2), forming an obstruction in the path of the crank arm head 40 when the crank arm is swung rearward to open the mechanism. In case the firing pin, for any reason, should stick in the hole provided for it in the front face of the block, it will thus be forcibly drawn back at the beginning of the turning of the operating crank 39 and before the block begins to move, the first part of the crank groove being curved concentrically around the axis of the crank 39. 130

80 is a cartridge case extractor and 88 a plunger acting as a latch for the extractor, the construction and operation of which are set forth in my said application Serial No. 5 151,407. The plunger 88 is actuated by a spring 89, which actuates a second plunger 91, which constitutes a latch for the collar of a stop bolt 92. The end of this bolt works in a groove 93 in the breech block 10 (said groove being inclined parallel with the wall 36), thereby limiting the travel of the block in the breech.

A firing handle 100 is slidably mounted on a non-recoiling portion of the carriage. 15 In this case it has been shown on the shoulder piece. The two shoulder piece arms 101, which are hollow, form guides for the firing handle. In one of these arms a rod 102 is carried. This rod is provided 20 with a stud 103, which projects through the wall of the arm and has positive engagement with the firing handle 100. A hook 104 at the forward end of the rod 102 engages a horn 105 of a bell crank 106, turnably 25 mounted on the breech end of the gun. The depending arm of the bell crank is connected by means of the trigger link 68 with the trigger 64. A spring 108 acts upon the bell crank 106 to cause it to exert a slight pull on 30 the trigger when the parts are at rest, thus providing an additional safety for withdrawing the firing pin from the primer when the mechanism is closed.

The mechanism operates as follows:—

35 Assume the gun to be loaded and the mechanism closed, as shown in Fig. 3. A continuous pull on the firing handle 100 will then be communicated to the hammer 45 through the intermediary of the parts 103, 40 102, 104, 106, 68, 64, 63, 47, 53 and 55, and the hammer, with the firing pin, will thus be retracted. During its rearward travel the hammer will be simultaneously turned through the engagement of the keys or lugs 45 59 in the helical slots 58. As now the pull on the trigger is continued, as communicated from the handle 100, the hammer lugs will eventually slip off the sleeve lugs 53, whereupon the hammer will be sent forward 50 by the main spring 50 and fire the primer. As the rocker 69 at this time is held against the spring 73, there is no obstruction to the hammer's forward movement. Directly the gun has been fired it begins to 55 recoil, and, as the firing handle 100, with the rod 102, does not partake in the recoil, the bell crank 106 is now released even if the firing handle should still be held back, and as a consequence the spring 52 will send the 60 sleeve forward. The sleeve, being keyed in a straight groove, proceeds in a straight path and compels the hammer 45 to turn sidewise when the lugs 55 hit the lugs 53. Directly the lugs have passed each other, 65 the hammer turns back so that the hammer

lugs stand right behind the sleeve lugs. Simultaneously the sleeve hits the head 72, causing the rocker 69 to tilt, whereby the head 71 engaging the hammer 45 will send the latter rearward, thus retracting the firing pin 46, which now retires behind the front face of the breech block, as shown in Fig. 10.

On now opening the mechanism, which will either be accomplished by hand, or, if 75 an automatic opening device is employed, by the latter turning the operating crank 39 during the recoil or counter recoil of the gun, the crank head 40 immediately moves out of the cam-groove 41 the arm 76 of the 80 hammer crank, the other arm 75 of which draws back slightly the hammer 45, through the intermediary of the sleeve 47, in case the rocker, for any reason, should have failed to do its work. Not until this is done does 85 the breech block begin to move. During the outward travel of the breech block the cartridge case is first loosened and then extracted; the extractor in its retracted position locking the block in its open position, as fully described in my said application Serial No. 151,407.

Upon again loading the gun, the rim of the cartridge case engages the toe of the extractor 80, drawing the latter forward, thus 90 releasing the block, which will now be pushed in, to close the mechanism actuated by the operating crank 39. It should be noted that the hammer does not become cocked during the opening and closing of 100 the mechanism. Except for the slight withdrawal of the firing pin for the sake of safety, the firing gear does not move; the cocking and firing all being accomplished by means of a single pull on the firing 105 handle 100, or on the trigger 64 if the firing handle should be dispensed with.

Having now fully described my invention, what I desire to claim and protect by Letters Patent is:

1. In firing mechanism for guns, the combination with an axially operable firing member, a slideable cocking member movable parallel with the firing member, and springs for said members tending to push them forward; of a third member positioned to engage both of said members when the parts are at rest and operable by the cocking member to slightly withdraw the firing member from the primer, the relative tension of said 115 springs being so adjusted as to permit the cocking member to so operate.

2. In firing mechanism for guns, the combination with an axially operable firing member, a slideable cocking member movable parallel with the firing member, and springs, one for each of said members, tending to push them forward; of a rocking lever engaging the firing member and the cocking member, the fulcrum point of the 120 125 130

lever being so positioned that, in coöperation with the relative pressures of the two springs, the firing member will be retracted.

3. A continuous pull firing gear for guns having a breech block, comprising two axially slidable members within said block, one of which is a cocking member and the other of which is provided with a firing pin, said members having interengaging lugs, a spring for each of said members tending to move the members in the direction of the firing primer, means for retracting the cocking member, whereby said firing pin member will be simultaneously cocked through the intermediary of said lugs, a bridge member engaging both said members when not actuated by said means thereby slightly retracting said firing pin member, the relative tension of said springs being so adjusted as to permit said members to so operate, and other means for causing disengagement between said lugs by said retraction, thereby setting said firing pin member free to be thrown by its spring against the firing primer.

4. A continuous pull firing gear for guns having a breech block, comprising two axially slidable members within said block, one of which is a cocking member and the other of which is provided with a firing pin, said members having interengaging lugs, a spring for each of said members tending to move the members in the direction of the firing primer, means for retracting the cocking member, and a stationary element, said firing pin member being axially guided in said stationary element and in said cocking member.

5. A continuous pull firing gear for guns having a breech block, comprising two axially slidable members within said block, one of which is a cocking member and the other of which is provided with a firing pin, said members having interengaging lugs, a spring for each of said members tending to move the members in the direction of the firing primer, means for retracting the cocking member, a stationary element, said firing pin member being axially guided in said stationary element and in said cocking member, and means on said element and said firing pin member for revolving said firing pin member for the purpose of gradually disengaging said lugs during the retraction of said members, whereby said firing member will be set free to advance and fire the primer.

6. In firing mechanism for guns, the combination with an axially operable firing member, a slidable cocking member surrounding the firing member and movable parallel with the firing member, and springs for said members tending to push them forward in longitudinal direction, lugs on said members situated one behind the other for

longitudinal engagement, means for moving said firing pin member in transverse direction whereby the latter member will, first, be retracted through the intermediary of said lugs during the rearward movement of said cocking member, second, set free through the intermediary of said means, and lastly, advanced by the action of its spring to fire the primer.

7. In firing mechanism for guns, the combination with an axially operable firing member, a slidable cocking member surrounding the firing member and movable parallel with the firing member, and springs for said members tending to push them forward in longitudinal direction, lugs on said members situated one behind the other for longitudinal engagement, means for moving said firing pin member in transverse direction, whereby the latter member will, first, be retracted through the intermediary of said lugs during the rearward movement of said cocking member, second, set free through the intermediary of said means, and lastly, advanced by the action of its spring to fire the primer, said lugs having beveled sides co-acting upon the ultimate release and advancement of said cocking member to push said firing pin member in transverse direction to permit said cocking member to pass and engage with its lugs in front of said firing pin member.

8. A continuous pull firing gear for guns having a breech block, comprising two axially slidable members within said block, one of which is provided with a firing pin and the other of which is a cocking member surrounding the firing pin member, said members having interengaging lugs, a spring for each of said members tending to move the members in the direction of the firing primer, means for retracting the cocking member, whereby said firing pin member will be simultaneously retracted through the intermediary of said lugs, and other means, comprising a helical groove in said block and a corresponding projection on said firing pin member, for causing disengagement between said lugs by said retraction, thereby setting said firing pin member free to be thrown by its spring against the firing primer.

9. A firing mechanism for guns comprising a firing member and a cocking member, means for moving said members parallel to each other in direction of firing the gun, and a rocking organ constructed to engage both of said members temporarily when the parts are at rest, the fulcrum of said organ being situated between its contact points with said two members, whereby the rocking organ, when actuated by said cocking member, holds the firing member in a slightly retracted position.

10. A continuous pull firing gear for guns

having a breech block, comprising two axially slidable members within said block, one of which is a cocking member and the other of which is provided with a firing pin, said
5 members having interengaging lugs, a spring for each of said members tending to move the members in the direction of the firing primer, means for retracting the cocking member, said means comprising a trigger
10 engaging said cocking member and fulcrumed in said block, a firing crank having connection with said trigger and being mounted to oscillate on the gun, and a spring tending to withdraw said firing pin member
15 from the primer into safe position.
11. A continuous pull firing gear for guns having a breech block, comprising two axially slidable members within said block, one of which is a cocking member and the other of which is provided with a firing pin, said
20

members having interengaging lugs, a spring for each of said members tending to move the members in the direction of the firing primer, means for retracting the cocking member, said means comprising a trigger 25 engaging said cocking member and fulcrumed in said block, a firing crank having connection with said trigger and being mounted to oscillate on the gun, and a spring tending to withdraw said firing pin 30 member from the primer into safe position, a slidable handle and a guide therefor, and a connecting member positively engaging said handle and releasably engaging said firing crank, said guide and handle being 35 mounted on a non-recoiling part.

In testimony of which invention, I have hereunto set my hand, at Philadelphia, on this 12th day of February, 1917.

HERMAN JAKOBSSON.
